A. HACKETT

TOBACCO PIPE

Filed March 3, 1923

Fig. 1.

Fig. 2.

Inventor:

A. Hackett

By Egerton H. Case,

Atty.

UNITED STATES PATENT OFFICE.

ALFRED HACKETT, OF TORONTO, ONTARIO, CANADA.

TOBACCO PIPE.

Application filed March 3, 1923. Serial No. 622,583.

To all whom it may concern:

Be it known that I, ALFRED HACKETT, a subject of the King of Great Britain, residing in the city of Toronto, county of 5 York, Province of Ontario, Canada, have invented certain new and useful Improvements in Tobacco Pipes, of which the following is a specification.

My invention relates to improvements in 10 tobacco pipes, and the principal object of my invention is to construct a tobacco pipe which will insure at all times the freedom from saliva of the tobacco in the bowl, thus insuring a "sweet" smoke. Another object 15 of my invention is to construct my pipe so that the mouth piece may be readily removed from the stem to permit of thorough cleaning, and in the following specification I shall describe a disclosure within my invention, and what I claim as new will be set forth in the claim forming part of this specification.

Fig. 1 is a vertical central longitudinal section through a pipe embodying the principle of my invention, and Fig. 2 is a vertical cross-section on the line 2—2, Fig. 1.

In the drawings, like characters of reference refer to the same parts.

The stem A of the bowl B is provided 30 with a uniform bore C for the major portion of its length, larger than the usual bore, and this uniform bore is provided with the uniform lining D, made of metal. There is no necessity of removing the lining D when 35 it has been placed in position, as the neck E of the mouth piece F is removably supported in the outer end of said lining, which outer end is preferably flanged as shown at G so as to face against the outer end of the 40 stem A. The inner end H of said lining is closed, except for an opening through which extends a conduit I which fits a hole J formed in the bottom of the bowl B and opening into the bottom of the cavity in 45 said bowl at one side thereof in the usual way. This conduit I is coupled to the lining D through the medium of the inner end H thereof so that said conduit will be positioned when said lining is positioned.

50 Mounted within the mouth piece F and

projecting beyond the inner end thereof into the lining D is a conduit O, preferably the same diameter as the conduit I, and substantially in alignment therewith. As will appear from the drawings, the opposed ends of the conduits I and O are spaced apart, and said conduits are of less external transverse diameter than the internal transverse diameter of the lining D.

The lined bore C, in combination with the 60 conduits I and O, form a well or trap, and it is evident that the saliva flowing down said conduit O will pass into the said trap or well, in place of continuing through the conduit I into the cavity of the bowl B.

It is believed that a considerable percentage of the waste products of combustion, so to speak, contained in the smoke from the smouldering tobacco, as the smoke leaves the conduit I, will remain in the well or trap, 70 thus appreciably reducing the percentage of such waste products of combustion that reach the smoker's mouth.

The tobacco in the bowl B will be free of admixture with the saliva, and a cooler 75 and sweeter smoke will result.

What I claim is:

A tobacco pipe having a bore of uniform diameter longitudinally formed in the straight stem thereof for the major portion 80 of its length, the inner end of said bore terminating short of the cavity in the bowl; a metal lining of uniform diameter having a circular inturned flange at its inner end permanently mounted in said bore, and having its flanged inner end fit against the inner end of said bore; a metal conduit having its inner end mounted in that portion of the bowl of the pipe separating the inner end of said bore from said cavity, and extending 85 through the inner end of said lining; a mouth piece having a neck adapted to fit within the outer end of said metal lining and a metal conduit mounted within said mouth piece for the length thereof and extending beyond said neck into said metal lining, the inner ends of said conduits being 90 spaced apart.

ALFRED HACKETT.
